UNITED STATES PATENT OFFICE.

WILSON G. H. RANDOLPH, OF NEW YORK, N. Y., ASSIGNOR TO ENDURANCE TIRE & BUBBER COMPANY, OF NEW BRUNSWICK, NEW JERSEY, A CORPORATION OF NEW JERSEY.

DESIGN FOR A VEHICLE-TIRE.

48,693.

Specification for Design.

Patented Mar. 7, 1916.

Application filed December 18, 1915. Serial No. 67,671. Term of patent 14 years.

To all whom it may concern:

Be it known that I, WILSON G. H. RANDOLPH, a citizen of the United States, residing at New York, in the county of New York and State of New York, have invented a new, original, and ornamental Design for Vehicle-Tires, of which the following is a specification, reference being had to the accompanying drawing, forming part thereof.

Figure 1, is a plan view of a portion of a

vehicle tire showing my ornamental design. Fig. 2, is a transverse sectional view of the same.

I claim:

The ornamental design for a vehicle tire, as shown.

WILSON G. H. RANDOLPH.

Witnesses:

FRANK R. TAYLOR,

FREDERICK E. IZZO.
